Primary Examiner — David G Muller(74) *Attorney, Agent, or Firm* — Leong C. Lei(57) **CLAIM**

The ornamental design for a multi-vortex tornado air circulator, as shown and described.

DESCRIPTION

FIG. 1 is a top isometric view of my multi-vortex tornado air circulator;

FIG. 2 is a top plan view thereof;

FIG. 3 is a bottom plan view thereof;

FIG. 4 is a side elevation view thereof;

FIG. 5 is an enlarged view of Detail 5 shown in FIG. 4;

FIG. 6 is a bottom perspective view of the multi-vortex tornado air circulator;

FIG. 7 is an enlarged view of Detail 7 shown in FIG. 6;

FIG. 8 is another bottom perspective view of the multi-vortex tornado air circulator; and,

FIG. 9 is an enlarged view of Detail 9 shown in FIG. 8.
